CLAIM

The ornamental design for a makeup brush as shown and described.

DESCRIPTION

FIG. 1 is a front, left, and top perspective view of a makeup brush, showing my new design;

FIG. 2 is a rear, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1;

FIG. 10 is a front, left, and top perspective view of a second embodiment of the makeup brush, showing my new design;

FIG. 11 is a rear, right, and bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is an enlarged view of an encircled area labeled "18" in FIG. 10;

FIG. 19 is a front, left, and top perspective view of a third embodiment of the makeup brush, showing my new design;

FIG. 20 is a rear, right, and bottom perspective view thereof;

FIG. 21 is a front elevation view thereof;

FIG. 22 is a rear elevation view thereof;

FIG. 23 is a left side elevation view thereof;

FIG. 24 is a right side elevation view thereof;

FIG. 25 is a top plan view thereof;

FIG. 26 is a bottom plan view thereof; and,

FIG. 27 is an enlarged view of an encircled area labeled "27" in FIG. 19.

The broken lines depict portions of the makeup brush that form no part of the claimed design.

The dot-dash broken lines in FIGS. 1, 9, 10, 18 and 19, 27, framing portions of the claimed design that are illustrated for enlargements form no part of the claimed design.

1 Claim, 27 Drawing Sheets
